BOILER CONTROL SYSTEM

Abner Doble, Berkeley, Calif.

Application May 5, 1930, Serial No. 449,786

16 Claims. (Cl. 122—448)

This invention relates to a system for control of a fluid heater such as a boiler and particularly to a heater of the series tube type. The fluid heater can be employed in a power plant for a mobile unit as an automobile or for stationary uses. I have employed the control system successfully with a boiler, operating on a fluid as water, in an automobile and shall preferably describe it in this connection.

10 It is a desideratum that the boiler be able to deliver steam having certain desired characteristics under substantially any load conditions. With previous boilers this has not been possible to the extent desired, the boiler being incapable, 15 under rapid fluctuations in load, or supplying large quantities of steam of the desired characteristics under all conditions so that the maximum effort could be secured from the device utilizing the steam.

20 In a co-pending application of Warren Doble, filed April 18, 1930, Serial No. 445,301, entitled "Steam power plant", it has been proposed to provide a boiler structure in which the quantity of heat released to the boiler may be augmented 25 so that any incapacity of the boiler to provide steam having the desired characteristics is not due to lack of heat.

It is accordingly, now possible to supply relatively great quantities of heat to the boiler so that 30 the thermal characteristics of steam generated in the boiler are maintained at the values desired. In accordance with the present invention, certain advantageous features of the aforementioned invention of Warren Doble are utilized to 35 provide a higher steaming capacity in which the increased quantity of heat is made available not only to maintain the temperature of the steam generated but also to provide for an increased capacity to furnish steam having the desired 40 characteristics. This invention works for a most economical method of operation for a steam power plant by controlling the quantity of water in the proper relationship to the quantity of heat supplied so that the boiler steams at a relatively 45 high rate.

In accordance with the present invention the operation of the means for releasing heat to the boiler is so regulated that the boiler furnishes steam of the desired characteristics substantially 50 in accordance with the demand for steam upon the boiler. This is largely due to the fact that I preferably coordinate the heat release means and the water supply means so that the water is proportioned to the heat released to the boiler.

55 While it is in general the broad object of the

invention to provide a boiler control system for securing the above advantages it is to be pointed out that the invention possesses other advantageous features and objects some of which with the foregoing will be set forth in the following specification and illustrated in the drawings accompanying and forming part of said specification. In the drawings I have shown forms of boiler control systems embodying my invention. It is to be understood that I am not to be restricted to these forms since the invention, as defined by the claims, may be embodied in other forms as well.

In the drawings, Figure 1 is a schematic showing of the boiler control system of my invention.

Figure 2 is a schematic showing of a similar system but including a different water pumping mechanism.

Figure 3 is a schematic showing similar to Figure 2 but with a simplified water controlling mechanism.

Figure 4 is a schematic showing of a further modified form of boiler control system in accordance with my invention.

My invention may be briefly characterized as comprising a boiler which is supplied with heat by suitable means and with water from a source of supply in accordance substantially with the demand for steam on the boiler, the quantity of the heat released to the boiler and the quantity 80 of water supplied being always in substantially predetermined mutual proportions despite variations in their rate of supply. Further, the system contemplates the regulation of the temperature of the steam leaving the boiler so that a predetermined temperature is maintained.

In the several forms illustrated in the drawings, a fluid heater 6 such as a boiler of the forced circulation type is formed by a relatively long tube 7 enclosed in a casing 8. The boiler is 95 heated by a fire provided upon ignition of a fuel-air mixture from carburetor 9. The carburetor 9 operates upon air which passes from a blower 11 through a conduit 12 into a venturi 13 at the throat of which the carburetor 9 is placed. The 100 carbureted fuel is ignited by the spark plug 14 as it passes into the boiler casing 8. The blower 11 is driven by an electric motor 23.

Steam generated in the boiler passes through the outlet pipe 16 to an engine indicated at 17, the 105 supply of steam being regulated by the throttle valve 18. Exhaust steam from the engine is preferably utilized to drive suitable power means for supplementing the electric motor furnishing the air-fuel mixture to the boiler, although steam can 110

be taken directly from the boiler, if desired, to drive the power means. To accomplish the supplementing of the blower by the turbine, conduit 19 conducts exhaust steam from the engine to a 5 turbine 21 mounted upon a shaft 22 upon which are mounted the blower 11 and electric motor 23.

Operation of the power plant is controlled by an electrical circuit which includes a generator 10 25 operated by the engine 17 to furnish current to a battery 26. The electrical circuit is traced through the battery 26, one side of which is grounded, a master switch 27, movable contact 28 associated with an adjustable fixed contact 29, a movable contact arm 31 associated with an adjustable fixed contact 32, solenoid valve mechanism 33 which controls admission of exhaust 15 steam to the turbine, electric motor 23, and mechanically actuated interrupter 36 and coils 37 which furnish the high tension current for the 20 spark plug. The movable contact 28 is operable by a pressure responsive device 38 to open or close the circuit in accordance with boiler pressure while the movable contact arm 31 is operable by a 25 temperature responsive device 39 such as a thermostat responsive to steam temperature in the tube 7.

When the master switch 27 is closed and the 30 circuit is completed through the contacts of the pressure and temperature responsive devices, current is passed from the battery to the solenoid 35 valve mechanism 33 which admits steam, if available, to the turbine. The electric motor 23 is also energized while current also passes through the mechanical interrupter 36 so that coils 37 supply high tension current to the spark plug 14 to ignite the fuel-air mixture which provides a fire in the 40 boiler casing.

When either the temperature or the pressure 45 have reached the predetermined value, the temperature responsive means or the pressure responsive means opens the circuit to deenergize the solenoid mechanism 33 so that steam is bypassed about the turbine 21, to deenergize the electric motor 23, and to deenergize the interrupter element and coils 37 so that no fire is supplied to the 50 boiler.

It is to be noted particularly that with the turbine 21 supplementing the motor to drive the blower, the fire in the firebox varies substantially 55 with the load on the engine and, further, with the demand on the boiler for steam. In accordance with the present invention the proper relationship is maintained between the variable quantity of fire and the variable quantity of water so that a maximum steaming rate is possible at all times. In that form of the invention shown in Figure 1, 60 water is supplied by a pump 51 drawing from tank 52. I prefer that the pump 51 be actuated by steam from the outlet conduit 16, the connection 65 being through a conduit 53 and the passage of steam to the pump being controlled by a solenoid throttle and valve mechanism 54. Also, I prefer, in accordance with my invention, that the admission of water to the boiler be controlled in accordance with such a boiler condition as the proportion 70 of heat available which is extracted by the water.

A manner of accomplishing this successfully 75 has been indicated diagrammatically in Figure 1 wherein temperature responsive means 66 such as rod 67 of non-expanding material is inserted in an expanding tube 68. The tube is positioned in the boiler so that it is affected by the fuel gases or products of combustion and is proximate 80 the boiler tube 7 to be affected thereby. The tem-

perature of the thermostat 66 on one hand is dependent upon the temperature and velocity of the surrounding fuel gases which, in turn are dependent upon the temperature of the proximate boiler tube 7. The thermostat 66 therefore assumes a temperature which is intermediate that of the boiler tube and that which the fuel gases would assume were the tube omitted, and which may be said to be a function of the proportion of heat extracted by the water from the heat available. An exact, mathematical expression of this function is unknown to me, but is immaterial in practice, as will subsequently be explained.

Joined to the thermostat rod 67 is a rocker arm 69 which carries a contact 71. When the temperature of the thermostat 66 is relatively high, the rod 67 is in such a position that the contact 71 is in abutment with fixed contact 72 to close a circuit 73. This circuit is traced through the contacts 71 and 72 through contacts 77 and 78 which control energization of the solenoid throttle and valve mechanism 54, to solenoid valve mechanism 74 which controls a bypass 76 from the pump.

In operation, when the temperature of the 100 thermostat 66 is low, the adjustable contact 71 is away from the fixed contact 72 and the solenoid throttle and valve mechanism 54 is deenergized to cut off steam to the steam pump. The solenoid valve mechanism 74 is also deenergized to 105 permit water to be bypassed from outlet 79 of the pump through a conduit 80 back to the tank 52.

When the temperature of the thermostat 66 increases, the rod 67 is moved to bring the contacts 71 and 72 into abutment with the result that the bypass valve is closed so that water can pass from the pump into conduit 81. From this conduit it passes to a metering device 82 having a passageway 83 therein. Communication of the 115 passageway with inlet 84 to the boiler is controlled by means of a valve rod 85 operated by the rocker arm 69 and having a tapered end projecting into the passageway 83. By shaping the tapered end properly, the unobstructed area of 120 passageway 83 can be fixed at any desired amount to pass a predetermined amount of water for any position, i. e. temperature, of thermostat 66. In practice the contour of the taper is determined experimentally for the particular system. It is 125 generally parabolic. The major consideration is that more water is passed to the boiler tube when thermostat 66 is relatively hot than is passed to the boiler when the thermostat 66 is relatively cold. The device 82 also includes a slidably piston 86 biased by a spring 87 and capable of maintaining a constant pressure drop across the valve 85. To accomplish this it moves up and down in the metering device to accommodate respectively for an excess or deficiency in the supply of water 130 from the pump. The piston 86 has a rod 88 which extends from the device and carries the contact 77. With an excess of water and an increase in the pressure drop, the piston rises to carry the contact 77 away from contact 78 so that admission of steam to the pump ceases and bypass 76 opens. With a deficiency in the supply 135 of water, the piston drops to bring the contacts 77 and 78 together so that steam passes to the pump and bypass 76 closes.

A portion of the water from the conduit 81 is preferably diverted to be introduced into the boiler to regulate with extreme accuracy the temperature of the steam therein. A solenoid valve mechanism 91 is included in a circuit with fixed 140

contact 92 and movable contact arm 93 which is moved by the temperature responsive means 39. When the temperature responsive means is actuated by an abnormally high temperature the contacts 92 and 93 abut so that the solenoid valve mechanism 91 allows water to pass into the boiler as at 94, to normalize or lower the temperature. The contact arm 93 is preferably closed before the temperature responsive means moves the movable arm 31 to open the circuit. In the form shown the normalizing of the temperature by the injection of water can occur after the supply of heat has been interrupted and as long as the pressure responsive contacts and master switch 15 remain closed, provided the pump 51 is operating because of closure of contacts 71 and 72 as well as 77 and 78.

In Figure 2 I have shown a modification of my invention. A water pump 101 is associated with the engine 17 and is adapted to be driven thereby. The pump draws water from the water tank 52 through inlet check valve 102 and discharges it through outlet check valve 103. A solenoid mechanism 104 is included in series with the contact 29 so that when the pressure responsive device 38 operates to open the circuit the check valve 102 is held off of its seat and water surges between the tank and the pump without being discharged past valve 103.

Water from the pump passes through a metering device 106 which includes orifices 107 and 108 in communication with the inlet 84 of the boiler. Control of the orifice 107 is preferably by means of a thumb screw 109 which can be adjusted to pass a quantity of water sufficient to accommodate for the minimum heating rate or the minimum quantity of heat which can be released to the boiler. To secure this, the temperature responsive means 66 connected to the rocker arm 69 is so designed that the valve stem 111 actuated by the rocker arm is placed in such a position, when the thermostat temperature is low, as to obstruct the orifice 108 so that the only water passed to the boiler is through aperture 107. However, when the temperature of the responsive means 66 rises, the valve mechanism 111 is caused to open the passageway through the orifice and allow additional water to pass to the boiler.

A piston 112 is also included in the metering device and is biased by a spring 113 so that it maintains a constant pressure drop across either one or both of the orifices. This is accomplished by providing the pump 101 with such capacity that an excess of water is always supplied to the metering device, the piston 112 bypassing any excess back to the tank 52 by means of a valve 114 which it operates and controls.

When the thermostat temperature is at a low value the orifice 108 is obstructed so that further water does not pass therethrough. If the pressure is low, the solenoid mechanism 104 is actuated to permit water to be passed to the boiler under the control of the pressure responsive device 38 which can, when the pressure is up, render the mechanism 104 effective to stop the pumping of water by holding check valve 102 open.

The modification shown in Figure 3 discloses an even simpler form of the invention. In this form, the check valve mechanism 104 is controlled by a circuit 121 which includes a contact 122 carried by the rocker arm 69 and a fixed contact 123. The circuit extends to the master switch 27 and, when the master switch is closed

and the temperature of the thermostatic element 66 is sufficient, the contacts 122 and 123 are brought together so that the check valve mechanism 104 is operated to drop the inlet check valve 102 so that water is supplied to the metering device from the engine operated pump. This metering device includes an orifice 126 controlled by valve mechanism 127 operable from the rocker arm 69. A slideable piston 128 is included in the metering device and is biased by spring 129 to maintain a constant pressure drop across the orifice 126 by diverting water to the tank 52 by means of the valve 131 which it carries and controls.

In the system of Figure 4, substantially the arrangement shown in Figure 1 is employed with the exception that the contact 77 is not connected to contacts, such as 71 and 72, operated by the thermostat 66, but is connected by a wire 132 to contact 29 of the pressure responsive mechanism.

I claim:

1. A boiler control system comprising a boiler, a fuel burner for supplying heat to the boiler, means for supplying water to the boiler, means for varying operation of the fuel burner so that under heavy load conditions the fuel burner supplies heat to the boiler at an augmented rate, and means responsive to the fuel gas temperature for controlling the supply of water independently of said varying means.

2. A boiler control system comprising a forced circulation boiler, means for releasing heat to the boiler, and means for supplying water to an intermediate part of the boiler in accordance with the temperature of the boiler steam and means for supplying water to the foot of the boiler in accordance with the temperature of the fuel gases.

3. A boiler control system comprising a forced circulation boiler, means for releasing heat to the boiler substantially in accordance with steam withdrawn from the boiler, means for supplying water to the boiler, a first means for controlling water supplied to the boiler in accordance with steam temperature therein, and a second means for independently controlling additional water supplied to the boiler in accordance with the temperature of the fuel gases.

4. A fluid heater plant comprising a forced circulation heater for the fluid, means for passing a heating medium over the heater to heat the fluid therein, means for supplying main and auxiliary feed fluid to the heater at thermally spaced points therein, and means responsive to the temperature of the heating medium for controlling the supply of main feed fluid only.

5. A boiler control system comprising a boiler tube, means for supplying heat to said tube by external combustion, means for supplying liquid to the inlet of said tube means responsive to steam temperature in said tube for controlling the supply of heat to said tube, and means responsive to the temperature of the products of said combustion for independently controlling the supply of liquid to the inlet of said tube.

6. A boiler control system comprising a forced circulation boiler tube, means for heating said tube by external combustion, a first thermostat responsive to temperature of the products of said combustion, a second thermostat responsive to temperature within said tube, means for supplying water to the foot of said tube under control of said first thermostat, means for supplying additional water to said tube immediately in ad-

- vance of and under control of said second thermostat, and means controlled by said second thermostat for interrupting the operation of said heating means.
5. 7. A boiler control system comprising a boiler tube having an inlet and an outlet, means for heating said tube by external combustion, a first thermostat responsive to temperature of the products of said combustion, a second thermostat responsive to temperature within said tube at a point between said inlet and said outlet, means for supplying water to the inlet of said tube under control of said first thermostat, means for supplying additional water to said tube between said inlet and said point under control of said second thermostat, and means responsive to a rise in temperature of said second thermostat above a predetermined value for interrupting the operation of said heating means.
10. 8. A boiler control system comprising a boiler tube having an inlet and an outlet, means for heating said tube by external combustion, means for supplying water to the inlet of said tube, means for supplying additional water to said tube at a point between said inlet and said outlet, a first thermostat responsive to the temperature of the products of said combustion, means controlled by said first thermostat upon a variation in the temperature thereof for varying the amount of said water admitted to said inlet, a second thermostat responsive to temperature within said tube between said point and said outlet, means controlled by said second thermostat upon an increase in the temperature thereof above a predetermined value for admitting said additional water to said tube at said point, and means controlled by said second thermostat upon an increase in temperature thereof above a higher predetermined value for interrupting the operation of said heating means.
15. 9. A boiler control system comprising a boiler tube having an inlet and an outlet, means for heating said tube, means for supplying water to the inlet of said tube, means for supplying additional water to said tube at a point between said inlet and said outlet, a thermostat responsive to temperature within said tube between said point and said outlet, means controlled by said thermostat upon an increase in the temperature thereof above a predetermined value for admitting said additional water to said tube at said point, and means controlled by said thermostat upon an increase in temperature thereof above a higher predetermined value for interrupting the operation of said heating means.
20. 10. A boiler control system comprising a relatively long boiler tube having an inlet and an outlet, means for heating said tube, means for introducing additional feed fluid into said tube between said inlet and said outlet, and temperature responsive means affected by said additional feed fluid for controlling said means for introducing additional feed fluid and for interrupting the operation of said heating means.
25. 11. A boiler control system comprising a boiler tube having a main feed fluid inlet and an additional feed fluid inlet, means for heating said tube, means for introducing feed fluid into said additional feed fluid inlet, and a thermostat responsive to tube temperature just beyond said additional feed fluid inlet for controlling said introducing means and for interrupting the operation of said heating means.
30. 12. A boiler control system comprising a boiler tube having a main feed fluid inlet and an additional feed fluid inlet, means for heating said tube, means for introducing feed fluid into said additional feed fluid inlet, means responsive to a predetermined temperature of said tube just beyond said additional feed fluid inlet for controlling said introducing means, and means responsive to a higher predetermined temperature of said tube for interrupting the operation of said heating means.
35. 13. A boiler control system comprising a boiler tube having an auxiliary feed fluid inlet between its ends and a main inlet and outlet at opposite ends, means for supplying feed fluid to said auxiliary inlet, means for heating said tube, and means responsive to temperature of said tube between said auxiliary inlet and said outlet for controlling said supplying means and interrupting the operation of said heating means.
40. 14. A boiler control system comprising a boiler tube having an auxiliary feed fluid inlet between its ends and a main inlet and outlet at opposite ends, means for supplying feed fluid to said auxiliary inlet, means for heating said tube, means responsive to a predetermined temperature of said tube between said auxiliary inlet and said outlet for controlling said supplying means, and means responsive to a higher predetermined temperature of said tube between said auxiliary inlet and said outlet for controlling the operation of said heating means.
45. 15. A boiler control system comprising a boiler, a variable fuel burner for supplying variable quantities of heat to the boiler, means for supplying water to the boiler, and means for controlling the water supply means independently of variations in the operation of said burner and in accordance with the fuel gas temperature.
50. 16. A boiler control system comprising a boiler of the forced circulation type, independently operable means for releasing heat in variable quantities to the boiler, independently operable means for supplying water to the boiler, and means for controlling said water supply means independently of variations in the operation of said releasing means and in accordance with the fuel gas temperature to coordinate the water supply to the heat released to the boiler.

ABNER DOBLE.
